Application November 19, 1947, Serial No. 786,977
In Italy November 23, 1946

4 Claims. (Cl. 116—121)

1

This invention relates to labels and more particularly to a label having an indicator associated therewith for conveniently presenting information to users of the devices to which the labels are applied.

An object of the invention is to provide a label having an indicator associated therewith which includes a movable pointer for selective cooperation with suitable indicia printed or otherwise provided on the label.

Another object of the invention is to provide a label in combination with an indicator which is constructed and arranged for attachment to various items, such as, by way of example, bottles, cases, boxes, and other containers for presenting, in an easy-to-read and understand manner, certain information as time, date, quality, quantity, weight and the like, relating to the articles or contents of the articles to which such labels are secured.

Still another object of the invention is to provide a label or mounting panel provided with suitable indicia, and a pointer which may be secured in operative relationship therewith at all times, or which may be associated therewith at the time the label or mounting panel is applied or secured to a container or similar article.

Another object of the invention is to provide an indicator having the hereinabove described characteristics wherein the pointer portion is mounted for restrained movement relative to the indicia of said label; or the pointer may be fixed relative to the indicia of the label.

Still another object of the invention is to provide an indicator type label having the hereinabove described characteristics which may be inexpensively fabricated using modern mass production methods.

These and other objects are attained by the means described herein and as disclosed in the accompanying drawings, in which:

Fig. 1 is a front plan view of an indicator label embodying the teachings of the present invention.

Fig. 2 is a front plan view of an indicator element, per se, comprising a detail of the invention.

Fig. 3 is a rear view of the label of Fig. 1.

Fig. 4 is a front plan view of a modified form of an indicator label comprising a detail of the invention.

Fig. 5 is a rear view of the panel of Fig. 4 with an indicator operatively secured thereto.

Fig. 6 is a rear plan view of a modified type of indicator label.

Fig. 7 is a front view of the label of Fig. 6 provided with an indicator and folded ready for use.

2

Fig. 8 is a front plan view of a blank layout of a so-called flag label.

Fig. 9 is a plan view showing a completed flag label of Fig. 8 provided with an indicator in association with a label.

Fig. 10 is a front plan view of another modified form of label comprising a detail of the present invention.

With reference to the figures, it will be noted that my indicator label comprises, broadly speaking, a label, base or mounting panel 10, an aperture 12, indicia 14 provided on one face of the label and along the axis of the aperture, and an indicator denoted generally by the numeral 16 (Fig. 2) which comprises a pointer portion 18 and an enlarged bearing portion 20.

With reference now to Fig. 2 it will be observed that indicator 16 may be fabricated from a single piece of material, such as, sheet metal, plastic, cardboard or the like, formed to provide a pointer portion 18 and an enlarged bearing portion 20. As illustrated, bearing portion 20 may be substantially circular in form and of an area greater than the area of aperture 12, wherein the enlarged bearing portion 20 comprises an interfering member of such a size as to preclude its passage thru aperture 12. The lower portion of pointer portion 18 may be defined by a pair of substantially parallel laterally spaced cuts 22 extending downwardly to an axis of the enlarged bearing portion 20. Pointer 18 is adapted to be folded downwardly about reference line 24 for disposing its base portion in spaced parallelism with portion 20.

An indicator may be associated with a label by introducing pointer 18 thru aperture 12 for overlappingly engaging the outer indicia-bearing face of the label and for disposing the enlarged bearing portion 20 in overlapping relationship with the rear faces of the label. In this manner pointer 18 may be simply and effectively mounted for movement relative to the axis of aperture 12.

In the preferred embodiment of the invention, the rear face of the label is adhesively coated as indicated by the numeral 26, thereby facilitating attachment of the label to a container.

With reference now to Fig. 3, it will be noted that an area 28 surrounding aperture 12 is not coated with adhesive which would interfere with the proper operation of the enlarged bearing portion 20 of the indicator. If desired, a shield element, approximating the area indicated by the numeral 28 of Fig. 3, may be secured to the rear, adhesively coated surface, of label 10 for provid-

ing a compatible bearing area for portion 20 of the indicator.

With reference now to Figs. 4 and 5, it will be noted that label 10 has been provided with a tab portion 30 having an aperture 32 for alignment with aperture 12 when tab 30 has been folded rearwardly in overlapping relationship with the rear adhesively coated surface 26 of the label. Tab 30 provides an adhesive-free surface for cooperation with bearing portion 20 of the indicator.

In Fig. 6 label 10 is provided with a flap portion 40 having an aperture 12 provided therethru. This flap is adapted to be folded about fold or score line 42 to overlappingly engage the rear, adhesively-coated, surface 26 of the label. An aperture 50 having its axis coincident with the axis of aperture 12 when flap 40 has been folded about score line 42 is provided thru the label, wherein the area of aperture 50 approximates the overall area described by rotation of pointer 18 about aperture 12. As disclosed in Fig. 7 indicia 14 is provided around the outer periphery of aperture 50. After an indicator has been associated with aperture 12 of flap 40, this flap may be folded to the position illustrated in Fig. 7, wherein it will be noted that pointer 18 overlappingly engages adhesively coated portion of flap 40. The label of Fig. 7 differs from those disclosed in the other figures in that pointer 18 may be secured or locked in a given position by effecting a bond between the adjacent faces of the pointer and the adhesive surface of flap 40.

In Fig. 8 a so-called flag type label is illustrated, said label including a front or indicia-bearing panel 60 having an aperture 12 with indicia 14 provided around the axis thereof. A mounting panel 62 and a shield panel 64 are provided on opposite sides of panel 60, said various panels being set apart by means of score or fold lines 66 and 68. In the preferred embodiment of the invention, the rear face of mounting panel 62 is provided with an adhesive substance. The blank of Fig. 8 is prepared for use by mounting an indicator relative to aperture 12, after which shielding panel 64 is folded rearwardly and in overlapping relationship with panel 60. Mounting panel 62 is then folded rearwardly on score or fold line 66 into overlapping relationship with the outer face of shielding panel 64, the remainder of mounting panel 62 extending beyond panel 60, thereby providing a mounting flap which, as illustrated, in Fig. 9, may be inserted beneath another label, denoted generally by the numeral 72, thereby thus providing said label with all the advantages of my indicator-label. If desired the blank of Fig. 8 may likewise be prepared for use by mounting an indicator 16 relative to aperture 12, folding shielding panel 64 rearwardly on scoreline 68 in overlapping relationship with panel 60. The rear face of panels 62 and 64 may then be adhesively coated for securing the flag label to a container, it being understood that suitable instructions may be placed or written directly on the front face of panel 62 thereby eliminating the need for a second or standard label 72.

With reference now to Fig. 10, it will be observed that aperture 12, instead of being circular, has been made in the form of an elongated slot, thereby enabling pointer 18 to be moved along a longitudinal axis rather than rotated about a fixed axis as is true in the labels of Figs. 1 to 9. The numeral 74 indicates generally that area of the rear face of the label which is

free of adhesive, in order to facilitate movement of the indicator relative to the label.

From the foregoing, it will be observed that I have provided a simple, yet highly efficient indicator label by means of which information may be quickly and accurately conveyed to users of the devices, and containers to which such labels are attached.

It should be understood that various changes and modifications in the structural details of the device may be made, within the scope of the appended claims, without departing from the spirit of the invention.

What is claimed is:

1. A label having a dial imprinted thereon and having an aperture provided therethru on the axis of said dial, an indicator mounted in said aperture including an L-shaped pointer portion one leg of which overlappingly engages that side of the label on which the indicia is provided the other leg of which extends through said aperture and terminates in an enlarged bearing portion formed integral therewith which engages the opposite face of the label for mounting said pointer for movement relative to the axis of said aperture, said bearing portion being of a dimension such as to preclude passage of said member thru said aperture.

2. A label including a body portion and a tab secured to and extending from one edge thereof, said body portion and tab each having an aperture provided therethrough, indicia provided on one face of said body portion adjacent said aperture, said tab foldable under said body portion and against its rear face for disposing said apertures in alignment, and an indicator mounted in said apertures, said indicator including a pointer which overlappingly engages the indicia-bearing face of said body portion and an enlarged bearing portion constructed and arranged to engage the rear face of said tab for mounting said pointer for movement relative to said apertures.

3. A label comprising a body portion and a flap secured to and extending from one edge thereof and having an aperture provided therethrough, said body portion having an aperture provided therethrough wherein the relationship of said apertures is such that their axes will coincide when said flap portion is folded into overlapping relationship with said body portion, adhesive material coating one face of said body portion and flap, an indicator mounted in the aperture of said flap, said indicator including a pointer portion which overlappingly engages the adhesive side of said flap, and an enlarged bearing portion constructed and arranged to engage the other side of said flap for mounting said pointer to movement relative to said aperture, indicia provided on that surface of said body portion opposite from the adhesively coated side around the periphery of the aperture provided therethrough, and wherein the area of said last mentioned aperture is approximately equivalent to the area swept by said pointer incident to its movement about the common axes of said apertures.

4. A flag-label comprising three interconnected panels including an indicia-bearing panel, having a shielding panel and an attachment panel extending from opposite edges thereof, said indicia panel having an aperture provided therethrough, an indicator mounted in said aperture including a pointer portion which projects through said aperture and overlappingly engages that side of the label on which the indicia is provided and an enlarged bearing portion which en-

gages the opposite face of the label for mounting said pointer for movement relative to the axis of said aperture, said shielding panel foldable rearwardly to overlie the rear face of said indicia panel and the bearing portion of the indicator, said attachment panel foldable rearwardly to overlie the rear face of said shielding panel and project laterally beyond the side edge of the indicia panel for providing an attachment tab.

10 HANS FRIEDLER.
